MACHINE FOR TURNING WOOD HEEL
BLANKS

Wilfred J. Grenier, North Rutland, Mass.

Application February 3, 1949, Serial No. 74,438

4 Claims. (Cl. 144—143)

1

The present invention relates to improvements in woodworking machines and more particularly, to improvements in wood-heel turning machines.

The primary object of the present invention is to provide a machine for automatically turning the two oppositely disposed side portions of a wood-heel blank in a manner which will enable this work to be performed by unskilled labor, with no more effort than is required merely to place the blank in the machine, which will securely clamp the blank and hold it in place during the turning operations, and will automatically discharge it at the end of the cycle of operations.

A further object of the present invention is to provide a machine of the above noted type which is so designed that it may be quickly and easily adapted for the automatic turning of different size wood heels by relatively unskilled personnel.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the accompanying drawings,

Fig. 1 represents a front elevation view of a machine in which the present invention is incorporated.

Fig. 2 represents a sectional view of the present machine taken substantially along the line 2—2 of Fig. 1.

Fig. 3 represents, on an enlarged scale, one of the several clamping heads which is employed on the present machine.

Fig. 4 represents a bottom plan view of the clamping head disclosed in Fig. 3.

Fig. 5 represents a sectional view of the present machine taken substantially along the line 5—5 of Fig. 1.

Fig. 6 represents a sectional view taken substantially along the line 6—6 of Fig. 1.

Fig. 7 represents, on an enlarged scale, a sectional view through an air valve, which view is taken substantially along the line 7—7 of Fig. 1.

Fig. 8 represents, on an enlarged scale, a sectional view through an air valve, which view is taken substantially along the line 8—8 of Fig. 1.

Figs. 9, 10 and 11 represent, respectively, the top, side and end views of a wooden heel blank of the type which is adapted to be fed to the present machine.

Figs. 12, 13 and 14 represent, respectively, the

top, side and end views of a heel, as the same is ejected from the present machine.

Fig. 15 represents, on an enlarged scale, a perspective view of a conveyor mechanism which may be used in conjunction with the present machine, for the purpose of successively placing a plurality of wood-heel blanks within the various blank gripping mechanisms carried upon the machine.

Fig. 16 represents a sectional view taken substantially along the line 16—16 of Fig. 15, and illustrates the conveyor mechanism as being provided with an air cylinder for feeding the heel blanks between the jaws of the clamping heads, one of which is disclosed in its blank-receiving position.

Fig. 17 represents a sectional view of a modified form of the present machine, which sectional view is taken substantially along the line 6—6 of Fig. 1.

As hereinabove noted, Figs. 9, 10 and 11 illustrate the heel blank of the type which is adapted to be fed to the present machine. It is to be noted that this particular blank is of a peculiar shape which has been imparted to the blank by means of a so-called cupping machine. Actually, such a cupping machine is adapted to receive a substantially rectangular shaped blank for the purpose of forming the so-called cup surface on the top portion of the blank. Figs. 10 and 11 particularly illustrate this cup surface which is slightly concave and is designated by the numeral 18. The present machine is adapted to receive these cupped blanks and to form at either side portion of the blank, a concave surface which is designated by the numeral 19. Upon completing the surfaces 18, 19, the heel is then in a completed state and may be secured to the sole portion of that type of shoe which is known in the trade by the term "wedges."

The present machine comprises a pair of laterally spaced frame elements 20 and 21 which are provided at their upper portions with bearing blocks 22, 22, for the purpose of receiving a substantially horizontally disposed main shaft 23. Surrounding but not secured to the main shaft 23 is a vertically disposed cam plate 24 which is supported upon spaced uprights 25, 25. Referring particularly to Figs. 1 and 5, there is secured to the shaft 23 a pair of spaced rotatable frame elements 26 and 27.

Secured upon the upright frame element 20, and between the two leg portions thereof, is a motor support platform 28 upon which is secured an electric motor 29. This motor is provided for

the purpose of rotating the shaft 23 in a clockwise direction, as viewed in Fig. 5. In order to so rotate the shaft 23, the motor 29 may be provided with a speed reduction means 38 which is ultimately connected with a small drive pulley 31. This drive pulley 31 is connected to a driven pulley 32 by means of a belt 33. The drive pulley 32 is rigidly secured to the shaft 23 and thus rotation of the motor 29 will drive the shaft at any desirable speed.

Referring now particularly to Figs. 1 and 5, the rotary frames 26 and 27 are each provided with a plurality of radiating arms 34, 34 which provide mounting means for a plurality of clamping heads which will be hereinafter more fully described. Rotatably mounted between a pair of the aligned arm portions 34, 34 of the spaced frame elements 26 and 27 are a plurality of rock-shafts 35, 35. Although the present invention contemplates the use of any reasonable number of such shafts, in the form of the invention herein illustrated, six shafts are employed. Referring particularly to Figs. 1, 3 and 6, it is to be understood that the righthand portion of each of the shafts 35, as viewed in Fig. 1, is rockably mounted within a respective one of the arms of the frame 27, while the other end portion of each of the shafts is similarly mounted within a respective one of the arms provided on the frame 26. Also, it is to be observed that the left-hand end portion of each of the shafts 35 is bent at right angles to the shaft proper, so as to provide a crank element 36. Mounted on the end portion of each of the cranks 36 is a cam follower element 37 which is adapted to track the various cams which are provided upon the inner face of the cam plate 24. The structure and function of the cam plate 24 will be described in more detail hereinafter.

As may be best observed in Figs. 1, 3 and 5, there is secured intermediate the end portions of each of the shafts 35, 35, a clamping head element which is generally designated by the numeral 38. More specifically, each of these clamping heads includes a frame element 39 which is secured directly and rigidly upon and intermediate the ends of its associated shaft 35. One edge portion of the frame 39 is provided with a blank-receiving slot 40. The right-hand end portion of this slot may have its face serrated, as at 41, to provide a stationary abutment member against which a wooden blank 42 may be secured by means of a movable jaw element 43. This jaw 43 is carried upon the distal end portion of a piston shaft 44, the other end portion of which extends into a hollow cylinder 45. A circular piston 46 carried upon the end portion of the shaft 44 is adapted to be actuated within the cylinder by air which enters the cylinder by means of a flexible hose 47. An air vent hole 48 is provided at the right-hand end portion of the cylinder to permit the free movement of the piston 46 which is normally biased toward the left-hand end portion of the cylinder by means of a coil spring 49. Thus, it is to be understood that the piston 46 is normally disposed at the left-hand end portion of the cylinder, whenever the air within the cylinder is at atmospheric pressure only. When the piston is in such a position, the movable jaw 43 is in its open or non-clamping position. Whenever air under pressure is introduced into the cylinder, the piston and piston shaft 44 will move in a right-hand direction, and thereby lock a heel blank 42 against the stationary jaw 41.

Mounted upon the right-hand end portion of

the clamping head 38 is a pattern member 50, the shape of which governs the actions of the present machine to the end that each of the blanks 42 is turned so that the blank, at the end of the machine cycle, will have a shape similar to that of the pattern 50. The function of the pattern 50 will be more fully described hereinafter.

Referring now particularly to Figs. 1, 2, 4, and 5, there is provided upon the frame member 21 and between the leg elements thereof, a supporting flange 51 upon which is secured an electric motor 52. This motor is adapted to drive a pair of cutting elements 53 and 54 which are mounted, respectively, upon a pair of parallel rotary shafts 55 and 56. More specifically, each of the shafts 55 and 56 is rotatably mounted within a respective one of a pair of stationary sleeves 57 and 58 which are, in turn, secured within a pair of cylindrical housings 59, 59. Referring particularly to Fig. 2, it will be observed that each of the cylindrical housings 59, 59 is mounted upon the frame element 21, and that the shafts 55 and 56 extend through their respective sleeve and housing members so as to have mounted upon their distal ends, pulley elements 60, 60. As may be best seen in Figs. 1 and 2, the upper pulley 60 is connected, by means of a belt 61, with a driving pulley 62 which is carried upon the end portion of the armature shaft 63 of the motor 52. This armature shaft 63 is also provided with a second pulley 64 which is connected to the lower pulley 60 by means of a crossed belt 65. From this, it will be appreciated that whenever the motor 52 is energized, each of the cutters 53 and 54 will be rotated in synchronism and in opposite directions from each other.

As may be best seen from Figs. 1 and 4, each of the cutter shafts' supporting sleeves 57 and 58 has mounted thereon a freely rotatable wheel element 66. More specifically, each of these wheel elements may be rotatably carried upon the sleeve, and a pair of snap rings 67, 67 function to retain the wheel in its proper axial alignment, due to the fact that each of the rings is received in the usual fashion within a groove provided within the sleeve 58. As will be hereinafter more fully described, each of the clamping heads 38, 38 is adapted to be rotated about the axis of the main shaft 23 in a manner such that its pattern element 50 will be first drawn over the upper guide wheel 66, to the end that the cutter 54 will turn one edge portion of a respective one of the wood-heel blanks in a manner as controlled by the shape of the pattern element 50. Thereafter, as the clamping head continues in its circular path, the pattern 50 is adapted to engage the lower control wheel 66, to the end that the cutter 53 will turn the opposite side of the wood-heel blank in a manner as controlled by the shape of the pattern element 50, thereby to complete the wooden heel.

As hereinabove noted, each of the clamp head supporting shafts 35, 35 is provided with a cam follower element 37 which is adapted to track the cams which are provided upon the inner face of the cam plate 24. As is best illustrated in Figs. 1 and 6, the cam plate 24 is provided with a primary stationary cam strip 68 which is rigidly secured to the frame. Also secured to the frame face are secondary stationary cam strips 69, 69' and 70. During the operation of the present machine, the unturned wood-heel blanks are inserted between the jaws of each of the clamp heads, while the head is in a horizontal position, as indicated by that head shown in the upper

left-hand portion of the Fig. 5. As soon as the blank is inserted between the jaws, air is introduced into the cylinder 45, to the end that the heel blank is rigidly clamped in place. Appropriate mechanism, which will hereinafter be described, functions both to introduce the air within the cylinder, for the purpose of clamping the blanks, as well as to cause the evacuation of the cylinder, for the purpose of permitting the finished heel to drop away from the machine and into a tote box or upon a continuously moving conveyor system.

Still referring to Figs. 1, 5 and 6, it is to be noted that each of the cam followers 37, 37 rests against the upper left-hand outer edge portion of the cam track 68, as its clamping head commences its cycle of rotation. Continued movement of the main shaft 23 causes the clamping heads to be carried about the shaft, and it is manifest that the positions of the individual clamping heads are entirely determined and controlled by the positions of the cam followers 37. It will be noted that the upper right-hand edge portion of the cam track 68 curves downwardly, as at 71, thereby to cause each cam follower to engage the upper portion of a bell crank cam 72 which is pivotally mounted upon the cam plate 24 by means of a pin 73. A spring 74, having one end secured to the plate 24, and its other end secured to one end of the bell crank cam, functions to urge a cam follower 37 in a counter-clockwise direction, to the end that its associated pattern element 50 will forcibly engage the upper control wheel 66. From this, it will be appreciated that the movements of the clamp head about its pivotal axis is thereafter controlled for a definite interval by the shape of the pattern member 50. Furthermore, as the clamp head is pulled past the control wheel 66, the upper cutter 54 will function to turn one side of the heel blank 42 so as to shape the heel blank in a desired manner as controlled by the shape of the pattern element 50. Upon the completion of each initial turning or cutting cycle, each cam follower 37 will be delivered between the two curved stationary cam strips 69 and 69' which will control the movements and position of the clamp head, as the same continues in its rotative movements about the axis of the shaft 23.

When each of the cam followers 37 reaches the lower portions of the stationary cam strips 69 and 69', it will be delivered between the upper edge portions of a pair of pivoted cam strips 75 and 76. More specifically, the lower cam strip 75 is pivotally mounted upon the cam plate 24 by means of a pivot pin 77, while the upper cam strip 76 is similarly mounted upon a pin 78. A flat spring element 79 carried upon the plate 24 by means of a pin 80 functions to bias the cam strip 76 in a clockwise direction about its pivot pin 78 and against the strip 75. Thus, it will be appreciated that as a cam follower 37 is delivered between the cam strips 75 and 76, it will be biased by means of the spring 79 in a clockwise direction, to the end that the pattern element 50 will engage the lower control wheel 66. Thus, as the clamp head is rotated about the axis of the shaft 23, the heel blank 42 will engage the lower rotary cutter 53, to the end that the other side portion of the blank will be turned in a manner as controlled by the shape of the pattern element 50, thus completing the secondary turning or cutting operation.

Referring particularly to Figs. 1 and 6, it is to be understood that the lower cam strip 75 is pivotally connected at its intermediate end portions

5 to the upper end portion of a piston rod 81 which is connected with a piston disposed within a dashpot cylinder 82. This dashpot cylinder 82 is of conventional design and functions as a shock absorber to prevent the wood-heel blank from being jolted into contact with the lower cutter 53 under the impetus of the spring 79.

10 After the second turning or cutting operation, each cam follower 37 will leave the cam strips 75 and 76 and engage the stationary strips 68 and 70. Continued rotation of the mechanism will permit each cam follower 37 to swing clear, under the force of gravity, from the primary cam strip 68, until the clamping head is positioned adjacent the curved upper left-hand portion of the strip 68, at which time the follower 37 will engage the outer periphery of the strip for the purpose of swinging the clamp head to a horizontal position, preparatory to receiving a fresh 15 wood-heel blank.

20 In order to control the opening and closing of the several movable jaws 43, 43, the present invention contemplates the provision of a special air valve which is best illustrated in Figs. 1, 6, 7, and 8. Referring particularly to Figs. 7 and 8, this valve comprises a stationary member 83 which surrounds the left-hand end portion of the shaft 23, and has its left-hand face portion secured directly to the cam plate 24. Cooperating 25 with the member 83 is a member 84 which surrounds and is secured to the shaft 23 so as to rotate in synchronism therewith. However, as will be particularly observed in Fig. 1, the respective face portions 85 and 86 of the members 83 and 84 are disposed in intimate contact with each other, and are adapted to rotate relative to each other during the operation of the machine. The stationary member 83 has an arcuate groove 87 formed in its face 85, and communicating with 30 this groove is an inlet aperture 88 which may be connected by means of a hose 89 (see Fig. 1) to a vacuum pump not herein disclosed. It will be understood that the aperture 88 extends through the cam plate 24 so as to be suitably connected 35 with the hose 89.

40 Also formed within the face 85 of the member 83 is a second arcuate groove 90 which is connected with the atmosphere by means of an aperture 91 which passes directly through the cam plate 24.

45 The member 84 of the air valve is suitably coupled directly to the shaft 23, and its face 86 is provided with a plurality of apertures 92, 92 which are so located thereabout that they will communicate with the arcuate grooves 87 and 90 of the member 83 as the member 84 rotates with the shaft 23. As may be particularly observed in Fig. 6, each of the apertures 92, 92 may be connected to a respective one of the air cylinders 45, 45 by means of a flexible-hose 47. From this, it will be appreciated that as the member 84 rotates in synchronism with the shaft 23, the various apertures 92, 92 will alternately be connected with the pressure chamber or groove 87 and the exhaust chamber or groove 90, to the end that the movable jaws 43, 43 will be actuated in a proper sequence. More specifically, the arcuate grooves 87 and 90 are so disposed within the stationary valve member 83 that they will cause the closing of each of the movable jaws 43, 43 whenever its associated cam follower 37 reaches the horizontal portion of the cam strip 68. Furthermore, the jaw will remain closed until the clamping head reaches a position adjacent the lowest point in its rotative movement,

at which juncture the turning or cutting cycles have been completed and thus, the clamp will then be permitted to open under the force of the coil spring 49. The completed wood heel will then drop away, under the force of gravity, from the clamp head and then fall into a tote box or upon a movable conveyor belt. From the above, it will be appreciated that the present machine is adapted for automatically turning or cutting the two oppositely disposed side portions of a wood-heel blank in a manner which will enable work to be performed by unskilled labor. In other words, with the exception of placing the individual blanks within the jaw portions of the clamping heads, the entire machine cycle is entirely automatic and no attention need be given to the machine by the operator with the exception of the feeding operation.

Furthermore, it is manifest that the present machine may be quickly and easily adapted for the automatic turning of different size wood heels by relatively unskilled personnel, for the simple reason that such a change over requires merely the removal of the various pattern elements 50, 50 and the replacement of these elements with new elements having a different size and shape. Such an operation merely requires a manipulation of a pair of pattern-securing bolts or screws 93, 93.

The present invention also contemplates the provision of means whereby the above described machine may be automatically loaded with wood-heel blanks. Referring particularly to Figs. 15 and 16, there is disclosed a pair of laterally spaced rollers 94 and 95, each of which is mounted upon a respective one of a pair of shaft elements 96 and 97, the opposite end portions of which may be rotatably journaled within the upstanding side members 98 and 99 of a sheet metal framework designated by the numeral 100. An endless belt 101 may be trained over the rollers 94 and 95, and for rotating this belt in a counterclockwise direction, as viewed in Fig. 15, the distal end portion of the roller shaft 97 may be provided with a belt pulley 102. An electric motor, not herein shown, may be provided for rotating the pulley 102 through the medium of a belt 103. As is particularly disclosed in Fig. 15, the framework 100 may be mounted upon suitably supporting legs 104, 104 so that the entire conveyor mechanism may be disposed in front of the machine in a manner such that the blanks may be conveniently fed to the various clamping heads 38, 38.

Still referring to Fig. 15, it is to be noted that the upper side portions of the framework 100 project upwardly above the upper surface of the endless belt 101 so as to function as guide elements. Furthermore, the left-hand end portion of the framework is provided with a curved apron or guide 105 which is spaced from and concentrically of the roller 94 so that it will provide between itself and the roller a passageway, the width of which is just sufficient to receive the heel blanks when they are fed to the guide side foremost. Spaced at the lower left-hand side portion of the roller 94 is a guide plate 106 which functions in conjunction with the lower portion of the apron 105 to house a single wood-heel blank and to support the same in a position 90° out of phase from that which it occupied while being fed along the belt 101. As may be particularly observed in Fig. 16, each of the side portions 98 and 99 of the framework are provided with aligned apertures 107, 107, which will permit

a wood-heel blank to be fed away from the conveyor and between the open jaws of one of the clamping mechanisms.

Still referring to Figs. 15 and 16, there is provided with the present conveyor mechanism an air cylinder 108 which is secured to one side of the conveyor by means of a flange 109. This air cylinder is provided with a piston 110 and has a piston rod 111, the right-hand end portion of which is aligned with the apertures 107, 107 and carries a blank-supporting member 112. The left-hand portion of the cylinder 108 is provided with an air hose 113 which may be connected with the above noted air pump. Thus, if air, under pressure, is delivered to the left-hand end portion of the cylinder 108, the piston rod 111, with its blank support 112, will move in a right-hand direction so as to feed a single wood-heel blank through the right-hand apertures 107 and between a pair of jaws carried on one of the clamping heads. As hereinabove noted, the jaw elements of the clamping heads 38, 38 are in an open condition when they reach the highest point in their path of travel, after which the above described valve mechanism 83, 84 functions to close the jaws. From this, it will be appreciated that the piston rod 111 should be synchronized with the motion of the shaft 23, so that a wood-heel blank 42 may be inserted within the open clamping jaws of each clamping mechanism just prior to the closing of the latter. In order to accomplish this objective, the present invention contemplates the provision of a three-way air valve mechanism 114 which may be mounted upon the upper portion of the cam plate 24 by means of a flange or angle plate 115. This valve mechanism may be of the usual commercial type which is provided with an actuating lever 116 which is normally biased into its closed position by means of a leaf spring 117. This handle member 116 is so positioned that it will be engaged by each of the cam followers 31, 31, as the clamping heads 38, 38 rotate in a clockwise direction, as viewed in Fig. 6. From this, it will be appreciated that such a valve 114 may be connected with the air hose 113 so as to fill the piston 108 with air, under pressure, whenever the valve 114 is tripped by a respective one of the cam followers 37, 37. After a cam follower has released the handle 116, it will be effective to exhaust the air cylinder 108 so that the piston 111 may be returned in a left-hand direction under the action of a coil spring 118 provided within the cylinder 108 and about the piston rod 111. In its normally inoperative position, the support member 112 of the piston rod 111 is disposed within the confines of the conveyor mechanism so as to receive thereupon a wood-heel blank, as the same is fed into the channel formed by the guide apron 105 and the wall member 106. Such a support member 112 will function to maintain the lowermost heel blank at a proper elevation during the feeding stroke of the piston rod 111, so that the blank will be properly positioned within the jaws of one of the several clamping heads. Furthermore, it is to be noted that the support member 112 is provided with an upper horizontal portion 119 which functions to engage that heel blank which is disposed adjacent the heel blank which is being fed toward the clamping head, so as to prevent the upper blank from interfering with the feeding motions of the piston rod 111. As soon as the piston rod is retracted into its inoperative or left-hand position, the member 119 will

release the block so that it may fall upon the support member 112, preparatory to the feeding of such a block into the jaws of an empty clamping head. From the above, it will be readily appreciated that the present conveyor mechanism is most simple and effective, for it will relieve the operator of the rather tedious job of placing a single heel blank within each of the clamping mechanisms 38, 38, as the same comes up into its heel-receiving position. Since the present machine is adapted to operate at a relatively high speed, it will be appreciated that without the present conveyor mechanism, an operator would soon be subject to extreme fatigue. However, the present conveyor mechanism will permit an operator to remove heel blanks from a tote box and place them upon a conveyor belt 101, with an expenditure of very little effort.

As hereinabove noted, the contours of each of the heel blanks is governed by the particular shape of the individual pattern elements 50, 50. In the event that the machine is to produce heel blanks having different contour shapes, it is necessary, with the above described mechanism, to remove the various pattern elements 50 and to replace them with pattern elements having different contours. The present invention, however, contemplates a modified form of the above described mechanism in which the six similar pattern elements 50, 50 may be entirely eliminated and replaced by a pair of cams or pattern elements 120 and 121 which are secured to the cam plate 24 in a manner as is particularly illustrated in Fig. 17.

Referring particularly to Fig. 17, it is to be noted that each of the cam elements 120 and 121 is rigidly secured to the face of the member 24, and cooperating with a respective one of these cams or pattern elements is a spring-biased member 122 and 123. More specifically, the upper member 122 is pivotally secured upon a pin 124 and is urged at all times toward the pattern element 120 by means of a leaf spring 125. Also, the lower member 123 is pivotally mounted upon a pin 126 and is urged toward its associated pattern element 121 by means of a leaf spring 127. Between the stationary pattern elements 120 and 121 may be positioned a stationary guide element 128, while another stationary guide element 129 may be rigidly secured to the plate 124 adjacent the end portion of the pattern element 121. The cam strip 68 which is disclosed in conjunction with the first described form of the present invention, may be retained in this second form of the invention. Thus, from the above, it will be appreciated that as each of the cam followers 37, 37 track about the stationary cam strip 68 in a clockwise direction, they will be ultimately delivered between the stationary pattern element 120 and the spring-biased element 122, so that the cam follower 37, as it continues to rotate, will be forced to follow the outline of the active portion 130 of the pattern element 120. This latter pattern element has its active portion 130 so shaped so as to successively force each of the wood-heel blanks against the upper cutter element 54 in substantially the same manner as is illustrated in Fig. 5. After the first cutting cycle is completed, the cam follower 37 will be delivered between the confines of the lower or secondary pattern element 121 and its cooperating member 123, the latter of which will force the cam follower to traverse the active portion 131 of the pattern element 121. The active portion 131 of this lower pattern ele-

ment will urge the wood-heel blank against the lower cutter 53 in substantially the same manner as is illustrated in Fig. 5. After leaving the pattern element 121, the cam followers 37 will traverse substantially the same path as was described hereinabove in connection with the first form of the invention. This modified form of the invention is advantageous in that it permits an operator to set up the machine for the production of different type wood-heel blanks by merely replacing the two pattern elements 120 and 121, whereas in the first form of the invention, it was necessary to replace six of the pattern elements 50, 50. In this connection, the present invention also contemplates the provision of adjustable pattern elements in lieu of the nonadjustable elements 120 and 121. A pattern element of the adjustable type is completely disclosed in my United States Patent No. 2,603,257, issued July 15, 1952, for Woodworking Machine. In the event that such adjustable pattern elements are employed in conjunction with the present machine, it will be manifest that the machine may be readily altered for the production of various size wood heels by merely adjusting each of the cam elements according to a predetermined schedule, thus obviating completely the necessity for the complete replacement of such elements.

30 I claim:

1. A wood shaping machine comprising, a pair of cutters each rotatably mounted about a respective one of a pair of laterally spaced axes, a plurality of work-holding clamps, a clamp-carrying frame rotatably mounted about a first axis disposed substantially in parallelism with the axes of said cutters, with each clamp rockably mounted about a pivotal axis movable with said frame, and laterally spaced from and disposed 35 in parallelism with said first axis, means for opening and closing said clamps in a predetermined sequence, means for rotating said frame to carry each of said clamps about the frame axis and past each of said cutters, and means 40 effective during continuous travel of the frame from one cutter to the other to oscillate each of said clamps about its pivotal axis thereby to control the cutting action of the cutters upon the work carried by the clamps and to cause each 45 clamp to have a first side thereof presented to one of said cutters and a second side thereof presented to the other of said cutters so as to cut successively the two opposite sides of each work piece.

55 2. A wood shaping machine comprising, a plurality of work-holding clamps, a clamp-carrying frame rotatably mounted about a common first axis, with each clamp pivotally mounted on said frame about a respective one of a plurality of secondary axes circumferentially spaced about and disposed in parallelism with said common first axis, means for opening and closing said clamps in a predetermined sequence, a pair of cutters each rotatably mounted about a respective one of a pair of laterally spaced axes located adjacent the circular path traversed by said rotating clamps, means for rotating said frame about said common first axis to carry said clamps past said cutters, and means effective during continuous travel of said frame from one cutter to the other to oscillate each of said clamps about its individual secondary axis thereby to control the cutting action of the cutters upon the work carried by the clamps and to cause each clamp to have a first side thereof

presented to one of said cutters and a second side thereof presented to the other of said cutters so as to cut successively the two opposite sides of each work piece.

3. A wood shaping machine comprising, a rotary main shaft, a work-carrying frame mounted on said shaft, a plurality of work-holding clamps each pivotally mounted upon and at circumferentially spaced locations about the periphery of said work-carrying frame, a pair of cutters each mounted upon a respective one of a pair of rotary shafts disposed adjacent the periphery of said work-carrying frame, means for rotating said main shaft so as to convey each of said clamps to and past said cutters, fluid-actuated means for opening and closing said clamps, a valve for controlling the supply of a fluid pressure medium to said clamps, to operate them in a predetermined sequence in response to the rotative movements of said work-carrying frame, a cam-follower member connected with each of said clamps, and cam means engaged by said cam-follower members so as to cause the clamps to oscillate about their respective pivotal axes thereby to control the cutting action of the cutters upon the work carried by the clamps and to cause each clamp successively to have a first side thereof presented to one of said cutters and a second side thereof presented to the other of said cutters in response to the continuous rotation of said main shaft through an angle corresponding to the peripheral displacement of said cutter shafts.

4. A wood shaping machine comprising, a rotary main shaft, a work-carrying frame mounted on said shaft, a plurality of work-holding clamps pivotally mounted upon and at locations spaced

10 15 20 25

circumferentially about the periphery of said work-carrying frame, a pair of cutters each mounted upon a respective one of a pair of rotary shafts disposed adjacent the periphery of said work-carrying frame, means for rotating said main shaft so as to convey each of said clamps to and past said cutters, means for opening and closing said clamps in a predetermined sequence in response to the rotative movements of said work-carrying frame, a stationary plate disposed adjacent said work-carrying frame, cam means disposed upon one face of said plate, and a cam-follower member connected with each of said clamps and extending into engagement with said cam means so as to track about said cam means in response to continuous rotative movements of said main shaft through an angle corresponding to the peripheral displacement of said cutter shafts, thereby to oscillate said clamps back and forth about their respective pivotal axes, said cam means being adapted successively to cause each clamp to have a first side thereof presented to one of said cutters and a second side thereof presented to the other of said cutters so as to cut the two opposite sides of each work piece.

WILFRED J. GRENIER.
